UNITED STATES PATENT OFFICE.

JOSEPH W. BARNA AND NATHAN A. THOMAS, OF CHICAGO, ILLINOIS.

EYELETING MACHINE.

Original application filed December 1, 1926, Serial No. 151,913. Divided and this application filed January 20, 1928. Serial No. 248,062.

This invention relates to improvements in eyeleting machines employed for setting eyelets in shoe-uppers and other articles with which eyelets are used.

The object of the present invention is to provide means in duplex machines of this character for laterally displacing or discharging the punchings from the punch-spindles and guiding them to a suitable point of deposit.

In machines of this type now in general use punching mechanism and eyelet-setting mechanism are arranged in top and bottom sets, above and below a common anvil, and both sides of the upper are eyeleted at the same time, eyelet holes being simultaneously punched in them and then eyelets are positioned and affixed in place in the holes. The punching and setting mechanisms with their common anvil are mounted on a movable head, and each punch and setting-plunger is operated by its own hammer; the punches to cut eyelet-holes in both sides of the shoe-upper, the set-mechanism to pick up eyelets and position them in the holes in the shoe-upper and to affix them therein, and then the punches to cut the next pair of eyelet-holes. The die or punch spindles are hollow and open at their outer ends, and the punchings are crowded through the spindles by the pressure of succeeding punchings and pass out of the open ends. As the hammers for the eyelet-setting devices are directly over and cover the open ends of the punch-spindles they prevent the use of a conduit to receive and convey the punchings away.

By our invention the punchings are positively displaced and discharged laterally from the punch-spindles, so that their egress is uniform and steady and a conduit can be used to guide them from the machine to any place of deposit.

Our invention consists in the organizations and arrangements of parts hereinafter described and claimed, and a practical embodiment thereof is shown in the accompanying drawings in which Fig. 1 is a view in front elevation of part of a duplex-set machine equipped with our invention; Fig. 2 is a view of parts of the same in side elevation taken on the punchings discharge side; Fig. 3 is a similar view taken on the opposite side; Figs. 4 and 6 are detail sectional views taken on the correspondingly numbered lines in Fig. 1, and Fig. 5 is a section on line 5—5 of Fig. 2.

In the drawings we show a punch- and set-head of a well-known type of duplex-set eyeleting machine comprising a body portion 1, upper and lower forwardly projecting arms 2 and 3 each having a vertically elongated bearing-block 4, and an anvil 5 fixed at its inner end on the head with its free end intermediate the blocks 4 and provided on its upper and lower faces with an inner punch-block 6 and an outer eyelet-setting die 7. Each bearing-block 4 is provided with inner and outer vertical guideways 8 and 9, respectively, the former being in axial alinement with the punch-blocks 6 and the latter with the set-dies 7. Reciprocating tubular punch-spindles 10 are located in the guideways 8 and are provided at their inner or facing ends with hollow cutting punches 11 to co-operate with the punch-blocks 6 to cut holes in the shoe-upper, and at their outer ends with laterally extended lugs 12 which run in guide-slots 13 in the same sides of the blocks 4; they are normally held in retracted position away from the anvil by spring-stressed levers 14 mounted on the machine and engaging cross-slots 15 in the lugs 12, and are projected for their cutting strokes by hammers 16 pivoted on the machine and suitably actuated to engage the lugs 12. Reciprocating set-sleeves 17 are located in the guideways 9 and are provided at their outer ends with laterally extended lugs 18 which run in guide-slots 19 in the same sides of the blocks 4. Each sleeve 17 is provided with a spring-pressed set-spindle 20 which picks up the eyelets from a feed-device and delivers them to the set-dies 7; the inner ends of the sleeves are formed to co-act with the dies 7 to affix the eyelets in the holes in the material, and each sleeve is operated for its setting stroke by a hammer 21 and is retracted by a spring-stressed lever 22 which engages its lug 18. The hammers 21 are pivotally mounted on the machine in rear of the bearing-blocks 4 and extend across and clear of the outer ends of the punch-spindles 10, and their faces are widened to remain in operative position with the sleeves 17 when the head is moved for the spindles 20 to pick up the eyelets and position them at the dies 7.

Our invention provides means for laterally displacing the punchings from the punch-spindles and discharging them through the bearing-blocks. Each punch-spindle 10 is provided on its side opposite its guide-lug 12 with an axially-elongated and laterally di-

rected discharge orifice 23, and the outer end of its bore is closed as by a plug 24 and the closure has a beveled or inclined inner wall 25 extending transversely of the bore at the outer end of its orifice 23 and in a direction away from its punch 11 to form a lateral guide to deflect the punchings out of the spindle through its orifice. Each bearing-block 4 is provided with a lateral passage 26 which registers with the orifice 23 when the spindle 10 is in its retracted position and during the movement of the spindle toward its punch-block and while the cutting operation occurs, and the lugs 12 and guide-slots 13 ensure their vertical alinement. Each passage 26 is provided with a conduit 27 to convey the punchings away from the bearing-block, and the conduits may be provided with flexible extensions 28 as shown to convey the punchings away from the machine to any place of deposit. When the machine is operated the punchings in the spindles are discharged laterally from the bearing-blocks instead of from the ends of the spindles. By this organization punchings-disposal con-

duits are arranged out of the way of the set, hammers or other necessary parts of the machine, and the objection to discharging the punchings out of the ends of the spindles is obviated. Also, the disposal devices are attached to the bearing-blocks and so are permanently mounted on the head. 30

This application is a division of our co-pending application filed December 1, 1926, Serial Number 151,913. 35

We claim:

In a duplex eyeleting machine, a head having upper and lower bearing-blocks, guideways in the blocks having lateral discharge passages through the blocks on the same sides, reciprocating tubular punch-spindles in the guideways and having lateral orifices in register with said openings, and inclined guides at the outer ends of said orifices to discharge the punchings through the latter. 40 45

In testimony whereof we affix our signatures.

JOSEPH W. BARNA.
NATHAN A. THOMAS.
